UNITED STATES PATENT OFFICE

1,997,952

STORE FURNITURE

Selene Woodside Snelling, Greenville, S. C.

Application August 7, 1933, Serial No. 684,099

3 Claims. (Cl. 20—1.6)

My invention relates generally to improvements in store furniture and the like, and has particular reference to a novel merchandising booth construction which is especially suitable for farm produce markets, mercantile exposi-
5 tions and the like.

Generally speaking the invention contemplates the provision of a novel merchandising booth construction for markets and the like which fur-
10 nishes improved individual booths for vendors, either singly or in connected series,—the nature of the construction being such as to provide for the attractive display of merchandise within convenient reach of the vendor, but beyond reach
15 of customers so that it will not become shop-
worn as the result of repeated handling.

The invention also aims to provide a mer-
chandising booth construction which may enable
20 the vendor to wait upon the trade while seated,
thus making it especially desirable for farm wom-
en's markets.

Further and more specific objects of the in-
vention are to provide, in a merchandising booth
25 construction,—(1) a novel combined counter and
door construction; (2) a novel easily operated
closure means for the open booth front that will
be out of the way when not in use, said closure
30 having locking means preferably cooperating
with the combined counter and door; and (3)
novel ventilating means for the booth.

The invention also resides in the various novel
features of construction, combination and ar-
rangement of the various parts to be hereinafter
35 described and claimed,—reference being had to
the accompanying drawings which illustrate what
now appears to be a preferred construction.

It should be understood that the specific
herein-disclosed embodiment of the invention is
merely illustrative, and that various changes
40 and modifications may be made therein within
the spirit and scope of the subject matter claimed
hereinafter.

In the drawings wherein the same reference
characters have been used to designate the same
45 parts in all views,—

Figure 1 is a horizontal sectional view through
a market building or the like and illustrating dia-
grammatically one installation of my booth con-
struction;

50 Figure 2 is a fragmentary perspective view
showing one end of a multiple booth-providing
unit;

Figure 3 is a cross sectional view through the
55 multiple booth-providing unit of Figure 2, giv-
ing an interior showing of one of the booths and

illustrating its closure in operative position for
holding the combined counter and door closed;

Figure 4 is a sectional view taken on the line
4—4 of Figure 3 for illustrating, mainly, the clo-
sure mounting and guide means;

5

Figure 5 is a horizontal sectional view taken on
the line 5—5 of Figure 3;

Figure 6 is a perspective of a single booth-
providing unit;

Referring specifically to the drawings, Figure 10
1 illustrates a building or room 7 having the front
entrance door 8 opening into the lobby 9. At
one side of the entrance 8 is the desk 10 for
the manager of the market or merchandising
room, while at the other side of the entrance 8 15
is a space for chairs 11 for the customers.

Still referring to Figure 1 it will be noted that
along each side wall is a multiple booth-provid-
ing structure indicated diagrammatically as at
12. At the rear of the building or room is shown 20
a booth structure 13 providing a refrigerator
counter means 13a. This latter type of booth
structure differs from those provided by mem-
bers 12 in that the counter 13a of each of the
booths provided by 13 is fixed and does not swing 25
as is the case with the counters of the booths
first referred to.

Referred to the booth-providing unit 12, as
shown in Figures 1, 2, 3, 4 and 5,—it will be noted
that the same provides end walls 14 which are 30
preferably paneled as indicated at 14a, 14b, in
Figure 2 and have the front and rear vertical
stiles or posts 14c, 14d, respectively.

Elongated tie strips or rails 15 (see Figure 3)
connect the end walls 14, and are also connected 35
to the intermediate vertical stiles or posts 18x,
carrying the partitions 17 that divide the struc-
ture 12 transversely into a plurality of booths,
as will be understood from an inspection of Fig-
ures 1 and 2.

40 Figures 2 and 3 disclose the narrow rearwardly
disposed top wall 16 of the unit 12 having the
ventilation opening 16a which is preferably
screened as at 16b,—there being the marginal
strips 16c for holding the screen 16b in place.

45 Below the top wall 16 at the front thereof
there is preferably provided the fascia board 16d,
which may be sectional or continuous, and pro-
vides a space for both numbers, or other indicia
as indicated. Top 16 may also have the mould-
ing 16e as shown.

50 From an inspection of the drawings it will be
apparent that each individual booth will be open
at the front, except for the gate and counter
structure 27, 28 to be referred to later on.

55

The panel-like partitions 17 and end walls 14 are substantially similar. Each has the rearwardly and upwardly curved frontal rails 22 and 23, the bottom rails 26, intermediate rails 24, the short top rails x, y,—and the partition stiles 18x, 25 correspond to end wall stiles 14c, 14d.

The rear partition stiles 18x carry, on each side thereof, strips 18 having grooves 18a while the corresponding end wall stiles 14c have similar strips 18 on the inner side only, all as shown in Figure 5. Also, it is evident from Figure 2 that both sides of curved partition rail 22 are grooved, whereas only one side of the corresponding rail 22 of end wall 14 is grooved for reception of the ends of closure members 21.

The closure 21 for the respective booths are preferably of the flexibly connected slat type generally similar to the well known "roll top desk" closure,—although other types may be used. Since the illustrated closure structure is the same in all booths a description of one will suffice for all.

As illustrated in Figure 2 and indicated in Figure 3, the vertical rear grooves 18a of opposite booth walls are adapted to receive the sides of the closure member 21 when the same is not in use. The flexible closure 21 in each instance is supported upon rotatably mounted disks 20 secured adjacent opposite side walls of each booth and adjacent the top wall 16.

Figure 4 best illustrates the mounting of the rotatable disks 20 and discloses the same as journaled upon pins carried by bearings 19. In the case of the end walls 14 a pin 19a secures bearing 19 to the end wall, but in the case of the partition structures 17 an elongated pin 19x secures bearings 19 against both sides of the partition between adjacent booths. In each instance nuts 19b serve to retain the disks on the bearing pins.

Figure 3 illustrates that the front wall portion of groove 18a in members 18 terminates adjacent the periphery of disk 20, as indicated at 18b, and this view also suggests that the rear wall of groove 18 may be curved forwardly around and spaced from the periphery of the adjacent disk 20 to provide, with the disk 20, a receiving groove 18c for the flexible cover 21,—as shown. This groove 18c communicates with grooves 22a in the rearwardly and upwardly curved frontal end wall and partition rails 22 as indicated in Figure 3. It should be understood that other suitable groove-providing means can be employed for guiding closure 21 about the disks 20.

The front of each booth is closed by means of a gate 27 which is hinged as at 27a to one of the front stiles or posts 25 and carries the horizontal counter 28 having the braces or supports 28a, which are illustrated in Figures 3 and 5.

Figure 5 also illustrates the counter as providing the lock-keeper 29 which is adapted to receive the bolt of the lock 30 which, as illustrated in Figure 2, is carried by the flexible closure 21. In this connection it will also be observed from Figure 2 that the lower rail of closure 21 has the handles 21a for convenient manipulation of same.

The rear end of the closure 21 is preferably weighted, as indicated at 21b to facilitate its movement; and there may be cooperating stops 21c on the rear end of the closure 21 and on the superjacent inwardly curved portion of member 18 above the groove 18a, as illustrated in Figure 3. These stops 21c may be omitted but are useful in that they engage to stop the rear end of closure 21 when the front end engages counter 28.

The gate 27 will preferably have the caster

support 27b at the end remote from the hinge 27a so as to support the weight of the counter and whatever may be upon the counter. Also, as indicated in Figure 2, the gate may have the latch 31, although it is particularly noted that the engagement of lock 30 with lock-keeper 29 when the closure or "roll-top" 21 is down will serve to keep the gate closed. This is a very important feature of the invention. The latch 31 is adapted to keep the gate closed while the booth is being used and the "roll-top" is up, as indicated in Figure 2.

Beneath the counter 28 is the till 32 pivoted to swing outwardly, as indicated at 32a, and having the guide or support 32b which is best illustrated in Figure 5.

As suggested in Figure 3, each booth wall 14, or 17 will have the vertical stile or post 33 connecting rails 24, 23,—said post or stile 33 being parallel with the adjacent rear posts or stile 18x and 14c.

Figures 2, 3 and 6 illustrate the shelves and supporting means therefor at the rear of the respective booths. In carrying out this phase of the invention, I provide metal strips 34 secured in one instance to the partition stile 18x and in another instance to the last-mentioned vertical stile or member 33 as indicated at 34b in Figure 3. These metal strips have suitable holes for the removable shelf supporting elements 36,—the holes being designed as at 34a.

Angle iron brackets 36a fixedly support and connect the lower shelf 35 to the frame,—the upper shelves being removably carried by the strip-carried fasteners 36.

Figure 6 shows a single booth unit whose side walls 14' provide the front and rear grooves 22a', 18a' for the "roll top" or flexible closure 21'. Closure supporting disks 20', corresponding to disks 20 of Figure 2, are there as indicated. The shelves 35' are supported in the same fashion as in Figure 3. The combination counter and gate is illustrated at 27', 28',—and a caster support 27b' is shown for the gate. Except for the fact that it is a single unit instead of a multiple booth-providing structure, the arrangement is the same as in Figure 2. One of the pivots for one of the disks is shown at 19'.

Swivel stools such as 51 may be put inside the respective booths so that the vendor can remain comfortably seated before the counter 28 or 28' and still reach the merchandise on the shelves. The doors or gates, such as 27, have openings 52 or 52' for ventilation, the circulation of air being upwardly through the screened openings 16a or 16a' in the top wall 16 or 16'. Referring to Figure 3 it will be seen that when the flexible closure 21 is in its operative position and locked to the counter 28, the weighted rear end 21a will be stopped just forwardly of the rear edge of the screened opening 16a in the top 16. Thus a circulation of air through the ventilating opening 52 of the door 27 will circulate upwardly past the shelves to reach the outlet opening 16a. Thus merchandise upon the shelves will be subjected to a cooling and ventilating draft when the booth is closed. Also bead moulding 54 may be disposed about the front and side margins of the top 16.

From what has been said it will be understood that a very efficient booth structure has been provided. The merchandise may be conveniently and attractively displayed on the shelves 35, or 35' in full view of the customers, but beyond their reach so that the produce will not be handled and become shopworn. Also when the closures 75

21 or 21' are pulled down and locked as at 29 or 29' to the counter 28, or 28', the gate is locked and the particular booth is shut up. The back of the booth structure is open and being against the wall will not afford a means of entry for unauthorized persons. It is understood, of course, that the booth structure may be suitably fixed to the floor. Even when closed a particular booth will be ventilated by air flowing in through gate 10 openings 52 under the gate 27, and from the rear, below the lower end of the "roll-top" closure member 21 upwardly through the screened openings 16a in the top.

Having thus described my invention, what I 15 claim as new is:

1. A merchandising booth comprising in combination a frame providing side and top walls, the top wall being very narrow as compared to the side walls and the latter inclining forwardly and downwardly from the top wall, shelving interposed between said side walls adjacent the rear of the frame and below said top wall, said side walls having opposed guideways adjacent their upper ends and extending forwardly from 20 said top wall, said side walls also providing opposed vertical guideways adjacent the rear of said frame, a flexible closure member adapted to assume a position in said first mentioned guideways for closing the front of the booth and adapted to assume a position in said second mentioned guideways for substantially closing the rear of said booth, and rotatable supporting means for said flexible closure interposed between said first and second mentioned guideways whereby 25 to establish communication between the same.

2. A merchandising booth comprising in combination a frame providing side and top walls, the top wall being very narrow as compared to the side walls and the latter inclining forwardly and downwardly from the top wall, shelving interposed between said side walls adjacent the rear of the frame and below said top wall, said side wall having opposed guideways adjacent their upper ends and extending forwardly from 40 said top wall, said side walls also providing opposed vertical guideways adjacent the rear of said frame, a flexible closure member adapted to assume a position in said first mentioned guide-

ways for closing the front of the booth and adapted to assume a position in said second mentioned guideways for substantially closing the rear of said booth, rotatable supporting means for said flexible closure interposed between said first and second mentioned guideways whereby to establish communication between the same, there being a ventilation opening in said top wall, a swingable counter adapted to close the lower front portion of said booth and carried by one of 5 said side walls, said counter providing a stop for limiting forward movement of said flexible closure, and the length of said flexible closure being such as to expose said top opening when such closure is engaged with said counter, and said 10 counter having ventilating means.

3. A merchandising booth comprising in combination a frame providing side and top walls, the top wall being very narrow as compared to the side walls and the latter inclining forwardly and downwardly from the top wall, shelving interposed between said side walls adjacent the rear of the frame and below said top wall, said side wall having opposed guideways adjacent their upper ends and extending forwardly from 20 said top wall, said side walls also providing opposed vertical guideways adjacent the rear of said frame, a flexible closure member adapted to assume a position in said first mentioned guideways for closing the front of the booth and adapted 25 to assume a position in said second mentioned guideways for substantially closing the rear of said booth, rotatable supporting means for said flexible closure interposed between said first and second mentioned guideways whereby to establish 30 communication between the same, there being a ventilation opening in said top wall, a swingable counter adapted to close the lower front portion of said booth and carried by one of 35 said side walls, said counter providing a stop for limiting forward movement of the flexible closure and the length of said flexible closure being such as to expose said top opening when such closure is engaged with said counter, said counter having 40 ventilating means, and cooperating locking means carried by said counter and flexible closure whereby they may be locked shut.

SELENE WOODSIDE SNELLING,
